COMBINED PHONOGRAPH PICKUP CARTRIDGE AND COVER THEREFOR

Machiel de Vries, De Kempenaerstraat 51,
Amsterdam, Netherlands

Filed Dec. 12, 1967, Ser. No. 9,747

Term of patent 3½ years

Int. Cl. D14—01

U.S. Cl. D26—14

FIG. 1

FIG-2FIG-3FIG-4FIGURE 1 is a perspective view of a combined phonograph pickup cartridge and cover therefor; showing my new design;

I claim:

The ornamental design for a combined phonograph pickup cartridge and cover therefor, as shown and described.
